ADJUSTABLE NOZZLE

Clarence R. Curtis, Lombard, Ill., assignor to F. H.
Smith Manufacturing Company, Chicago, Ill.,
a corporation of Illinois

Application August 16, 1947, Serial No. 768,952

8 Claims. (Cl. 299—136)

1

This invention relates to an improved fluid nozzle, and particularly to an adjustable nozzle for use as a garden hose nozzle, fountain spray, shower head, and similar applications.

A large number of adjustable nozzle constructions have been heretofore proposed and utilized. All of such previously known constructions have, however, been subject to one or more disadvantages. For example, the most common type of hose nozzle wherein a nozzle head is rotated to produce a variation of the spray emitting from the nozzle has the well known disadvantages of requiring a large amount of rotative movement, i. e., several turns, of the nozzle head to effect the spray adjustment and, furthermore, in being capable of interrupting all fluid flow through the nozzle at only one extreme rotative position of the rotatable nozzle head. Hence considerable manipulation of the nozzle head is required in ordinary usage, and it was generally necessary for the operator to devote both hands to the task of securing proper adjustment or cut off. Other well recognized defects of conventional nozzles are the ready tendency of such nozzles to leak after relatively limited service, the irregularity of the degrees of spray produced by such nozzles, the failure of such nozzles to produce a high velocity, cylindrical, stream of fluid for long distance projection, and the inability of such constructions to withstand any substantial amount of rough handling or usage. Many attempts have been made to overcome these well recognized disadvantages of conventional adjustable nozzle constructions but all such attempts have been commercially unfeasible inasmuch as they involved complications of construction or manufacture, which had the result of substantially increasing the manufacturing cost of the nozzles to a point where they could not be profitably placed in competition with the cheaper, but inferior nozzle constructions.

Accordingly, it is an object of this invention to provide an improved adjustable nozzle, and particularly a nozzle which will overcome all of the well recognized disadvantages of existing nozzles and yet embodies a simple, sturdy and rugged construction which may be economically manufactured by large quantity, low cost production methods.

A further object of this invention is to provide an improved adjustable nozzle embodying a rotatable nozzle head for controlling fluid flow through the nozzle and having the operating characteristic that very limited turning of the rotatable nozzle head will effect a full variation of spray characteristics of the fluid flow through the nozzle from a shut-off condition, through a cylindrical stream, through varying degrees of spray and then again to a shut-off condition, or vice versa, depending upon the direction of ro-

2

tation of the nozzle head. Furthermore, an adjustable nozzle embodying this invention may be conveniently manipulated by one hand of the operator.

5 Still another object of this invention is to provide an improved adjustable nozzle construction wherein fluid leakage from the nozzle under any conditions is positively prevented by a metal-to-metal seal, and such seal is maintained fluid-tight not only by the pressure of the fluid passing through the nozzle but in addition by a positive spring force.

10 A further object of this invention is to provide an adjustable nozzle construction capable of unusually economical manufacture in that substantially all of the components of the nozzle may be produced by automatic machinery of the automatic screw machine type.

15 Still another object of this invention is to provide an improved adjustable nozzle construction wherein substantially identical components may be utilized to produce nozzles for a variety of applications, such as for a garden hose nozzle and a shower head for bathroom usage.

20 Lastly, it is an object of this invention to provide an adjustable nozzle which is of extremely compact construction and incorporates a simple yet pleasing exterior configuration and in which the various components are of unusually rugged construction assuring a long service life of the nozzle even under adverse conditions of usage.

25 The specific nature of this invention as well as other objects and advantages thereof will become apparent to those skilled in the art from 30 the following detailed description taken in conjunction with the attached sheets of drawings which, by way of preferred example only, illustrate two embodiments of this invention.

35 On the drawings:
40 Figure 1 is an elevational view of an assembled hose nozzle embodying this invention;

45 Figure 2 is an enlarged scale, sectional view taken on the plane II—II of Figure 1 and showing the fluid flow control member of the nozzle in its forward extreme axial position;

50 Figure 3 is a view similar to Figure 2 but showing the fluid flow control member in its rearward extreme axial position;

55 Figure 4 is a transverse sectional view taken on the plane IV—IV of Figure 2;

Figure 5 is an enlarged scale, elevational view, partly in section, of the nozzle head element embodying this invention, showing in particular the formation of the spray controlling surfaces there-

55 of;

Figure 6 is an elevational view, partly in section, of the rear section of the fluid flow control member;

60 Figure 7 is an elevational view, partly in section, of the tail element of the nozzle head; and

Figure 8 is an elevational view, partly in section, along a plane passing through the axis, of a shower head construction embodying this invention.

As shown on the drawings:

As best shown in Figures 2 and 3, the hose nozzle embodying this invention comprises a hollow body member 10 which is of substantially concentric construction permitting such body member to be conveniently manufactured by automatic screw machine processes. The body member 10 has a bore 11 extending therethrough which bore is of variable diameter along the length of the body member 10 for purposes to be described later. The front end 10a of the body member 10 is cylindrical and of smaller exterior dimensions than the rear end 10b. The rear end portion may be provided with an external knurling 10c to facilitate the grasping of the nozzle by the hand of the operator.

From the front to the rear of the body member 10, the bore 11 is defined as follows: Immediately adjacent the front end thereof, an inwardly projecting shoulder is provided defining a small diameter bore portion 11a and having a conical, rearwardly facing surface 11b which is suitably finished so as to serve as one seating surface of a valve preventing fluid leakage from the nozzle. Next to the conical surface 11b there is provided a cylindrical bore portion 11h which provides a bearing surface for journaling the tail section 13 of the rotatable valve head 12. On the rearward side of cylindrical bore portion 11h, enlarged diameter, cylindrical bore portions 11c are provided which, however, are separated by a reduced diameter bore portion 11d, providing a shoulder therebetween. A pair of diametrically disposed, axially extending grooves 11e (Figure 4) are cut into the shoulder 11d to the depth of the bore portions 11c. At the extreme rear end of the bore 11, an enlarged diameter, threaded portion 11f is provided to receive the conventional threaded coupling of a hose or similar fluid conduit. The shoulder 11g between bore portions 11d and 11f provides a suitable seating surface for the customary rubber sealing washer (not shown).

A nozzle head unit 12 is provided having a generally cylindrical exterior front portion 12a and a reduced diameter tail portion 13 which may, for convenience of assembly, comprise a separate member which is threadably secured to front portion 12a as by threads 13a. In assembly, however, the threads 13a are drawn up very tight so that in ordinary usage of the nozzle the tail portion 13 acts for all practical purposes as an integral part of the front portion 12a.

To facilitate the assemblage of the tail portion 13 into the front portion 12a of the nozzle head 12, a pair of opposed flats 13e are provided on the rear end of the tail portion for engagement by a suitable tool. Flats 13e also serve to provide a flow path through the nozzle as will be later described.

Tail portion 13 has an intermediate neck portion 13b of suitable diameter to snugly fit within the bore surface 11a defined by the inwardly projecting shoulder at the front of body member 10. Rearwardly of neck portion 13b the tail section 13 has an enlarged diameter, cylindrical bearing portion 13c which is journaled by bore portion 11h of the body member 10. A conical surface 13d is provided to connect neck portion 13b and bearing portion 13c, and this surface cooperates with the conical surface 11b of the body

member to provide a fluid seal. It will be noted that the arrangement of the valve head 12 with respect to the body member 10 is such that the fluid pressure applied to the nozzle urges the sealing surfaces 13d and 11b together. In addition, an annular disc-type spring 15 may be mounted between the rear face of the front section 12a and the front face of the body member 10 to exert a further biasing action on the sealing surfaces.

A central passage 16 is provided entirely through the valve head unit 12 and communicating with the bore 11 of the body member 10. From the rear of valve head unit 12 to the front, 15 the passage 16 comprises the following elements: first, a threaded portion 16a is provided at the end of the tail portion 13. The threads 16a are preferably selected of high pitch so that a slight rotation of valve head 16, in any event not more than one turn thereof, will be sufficient to effect all the necessary axial movements of the fluid flow control member 20 as will be later described. Immediately forward of the threads 16a an enlarged groove 16b is provided which, in cooperation with the flats 13e, provide a flow path around the threaded end of rear section 20b of the flow control member 20. Forwardly of the groove 16b, a cylindrical bore section 16c is provided which is of sufficient diameter to provide a large clearance for unimpeded fluid flow around the flow control member 20 and also to provide bearing support for such member.

Forwardly of the cylindrical bore portion 16c, an inwardly projecting shoulder 17 is provided 35 defining a minimum diameter passage and on its rear side having a conically shaped surface 17a which functions as one of the sealing surfaces for cutting off fluid flow through the nozzle. Immediately forward of shoulder 17 the passage 40 16 is radially enlarged as indicated at 16d and then this surface blends with an inwardly tapering surface 16e which reduces the diameter of the passage toward the forward end thereof. The negative taper provided for the bore portion 45 16e, and indicated by the angle α in Figure 5, is of substantial importance in achieving high velocity, cylindrical stream of fluid for maximum distance projection. While the exact angle of such negative taper may obviously vary slightly according to the conditions of each particular nozzle design, a small angle on the order of 5° is preferably employed.

The reversely tapering bore portion 16e is terminated at a point where the minimum diameter 50 of such portion is still substantially greater than the bore diameter defined by the shoulder 17. At this point the bore 16 is again enlarged by a generally radial section 16f which blends into an outwardly flaring or tapering section 16g which 55 continues out to the end of the nozzle head 12. If desired, a slight conical counterbore 16h may be provided at the mouth of outwardly flaring portion 16g. The exterior surface of the front portion 12a of the nozzle head 12 is provided with 60 knurling 12b so as to facilitate the grasping and rotating of the nozzle head with respect to body member 10 by the fingers of the operator.

The control of fluid through the central passage 16 is effected by a fluid flow control member 20 65 which, while it operates unitarily, may conveniently comprise a threaded assembly of a front element 20a and a rear element 20b. A screw driver slot 20d may be provided in front element 20a to facilitate assembly.

A spray head 21 of generally bulbous configura-

tion is formed on the extreme front end of the flow control member 20. At least a portion of the bulbous head 21 is of greater diameter than the narrow bore defined by the internally projecting shoulder 17 so that in one axial position the bulbous head 21 will seat against the front face of shoulder 17 to effectively seal off all fluid flow through the nozzle. When the bulbous head 17 is first moved forwardly in the passage 16 from its sealing off position, an annular orifice will then be defined between the bulbous head 21 and the reversely tapering bore portion 16e. The fluid flowing through such annular passage will be discharged from the nozzle as a substantially cylindrical stream, and accordingly the fluid stream may be projected a maximum distance as determined by the pressure of the fluid. The distance of projection achieved by this construction is quite remarkable.

Still further forward movement of the bulbous head 21 will position such head within the outwardly flaring portion 16g of the nozzle head and, by virtue of the reflection of the fluid stream by the arcuate surfaces 21a of the bulbous head to impinge against the flaring wall of passage portion 16g, a spray will be produced whose characteristics will vary according to the axial position of the bulbous head portion 21 with respect to the flaring passage 16g.

At a point rearwardly spaced from the bulbous head portion 21, the fluid flow control member 20 is provided with a forwardly facing abutment surface 22 which may conveniently comprise the tapered front face of the rear section 20b of the composite fluid flow control member 20. This abutment surface or flange 22 is also of greater diameter than the passage defined by the inwardly projecting shoulder 17. Hence, when the fluid flow control member 20 is moved forwardly to shift the bulbous head portion 21 into cooperative relationship with the outwardly flaring passage portion 16f, the flange 22 will be brought into engagement with the rearwardly facing conical surface 17a provided on the shoulder 17 and effect a sealing off of all fluid flow through the nozzle in the other extreme axial position of the fluid flow control member 20. Hence, a full range of flow control is obtained including both a cylindrical stream and a variety of spray characteristics as well as a fluid cut-off condition at each end of the range.

The axial movement of the fluid flow control member 20 to effect the adjustment of flow control through the nozzle may obviously be accomplished in a variety of manners, but I preferably employ the rotation of the nozzle head 12 to produce such axial movement. This may be conveniently accomplished by providing threads 23 on the exterior of the rear element 20b of the fluid flow control member 20. These threads 23 cooperate with the high pitch threads 16a provided in the tail portion 13 of the nozzle head 12 and hence will produce an axial movement of the flow control member 20 if such member is prevented from rotation while the nozzle head 12 is rotated.

To prevent the rotation of fluid flow control member 20, yet to freely permit axial movement of such member, I preferably provide a bar 24 which extends transversely across the interior of body member 10 and the opposite ends thereof slidably engage in the axially extending grooves 11e. The bar 24 may be conveniently retained in assembly in the grooves 11e by staking in the ends of such grooves as indicated at 11j. The bar 24 may be secured to fluid flow control member 20

in a variety of manners, such as by providing an elongated slot 20c in the rear end of the fluid flow control member which snugly receives the bar 24 therein.

It is apparent that rotation of the nozzle head 12 will immediately result in an axial displacement of the fluid flow control member 20 between the limits of axial movement defined by the respective engagements of the shoulder 17 with the bulbous head portion 21 of the sealing off flange 22. To permit fluid flow through the threaded connection between the tail portion 13 and the fluid flow control member 20, in addition to that produced by the path provided by flats 13e, the rear section 20b of the fluid flow control member 20 is formed of generally square cross section and the threads 20b formed thereon are provided only at the corners of such square in the manner best shown in Figure 4. Hence, fluid flow may freely occur in the clearance between each of the square sides of the rear section 20b and the arcuately formed threads of the tail portion 13.

The ease and economy of manufacture of an adjustable nozzle constructed according to this invention is readily apparent from the foregoing description. Substantially all of the major components of the nozzle are of concentric configuration and hence may be readily produced by automatic screw machine methods. The formation of the valve head unit 12 and the fluid flow control unit 20 by threading together of two sections permits such elements to be conveniently assembled in the nozzle construction and automatically effects a permanent retention of such elements in assembly.

Although the overall dimensions of a nozzle construction embodying this invention are substantially less than that of conventional nozzles, yet all of the individual components thereof are of such sturdy design that such components may be conveniently manufactured from lightweight metals such as aluminum, magnesium or alloys of the same, without fear of structural failures even under adverse conditions of usage. Furthermore, the nozzle may be conveniently held by the operator in one hand and completely controlled by the fingers of the one hand. This leaves the other hand of the operator completely free which is of a decided convenience in manipulating a garden hose.

The fluid flow control elements of a nozzle construction embodying this invention may be incorporated without change in other forms of nozzles, such as a shower head. Referring to Figure 8, there is shown a shower head embodying an adjustable nozzle constructed in accordance with this invention. Similar numerals in Figure 8 refer to corresponding parts in the modification of Figures 1 through 7, and hence it will be readily observed that the tail portion 13 of the nozzle head unit, the fluid flow control unit 20, the spring 15, and the transverse bar 24 may be utilized in the shower head construction without change. The front portion of the nozzle head 40 embodies the same exterior configuration but, if desired, the exterior may be flared as shown at 40a.

To adapt the nozzle construction for use in the shower head, it is preferred to employ a body member 30 of somewhat different exterior configuration than the corresponding member 10 employed in the hose nozzle modification. Thus, the body member 30 of Figure 8 has a substantially identical interior bore construction as that

of the body member 10 heretofore described but on the exterior thereof is provided with an annular spherical segment surface 30a. A fitting 31 is provided having a neck portion 31a internally threaded to connect with a source of fluid in conventional manner and an enlarged mouth portion 31b having an interior, annular spherical segment surface 31c correspondingly shaped to the exterior surface 30a of the body member 30. Hence, the body member 30 may be swivelly supported within the fitting 31 and retained therein by a retaining nut 32 which is screwed into threads 31d provided in the mouth of fitting 31. To prevent leakage between the fitting 31 and the body member 30, an annular seal 33 is compressed therebetween in conventional fashion. Also, if desired, a plug 36 may be snugly inserted into the rear end of body member 30 so as to retain the bar 24 within the slot 11e and thus eliminate the staking operation which was employed in the hose nozzle modification.

Plug 36 is provided with a plurality of spaced apertures 36a to provide unimpeded fluid flow therethrough. If desired, the forward face of plug 36 may be located so as to limit rearward movement of the control member 20 to prevent fluid cutoff in the rear position of flow control member 20. Also, an axial flange 36b on plug 36 assists in compressing sealing washer 33.

In any event, it is apparent that the same range of fluid control and spray adjustment is provided in the shower head modification of Figure 8 as was heretofore described in connection with the hose nozzle modification. In addition, the direction of the fluid stream or spray may be conveniently adjusted by swivelling the body member 30 within the fitting 31.

It will, of course, be understood that various details of construction may be modified through a wide range without departing from the principles of this invention, and it is, therefore, not the purpose to limit the patent granted herein otherwise than necessitated by the scope of the appended claims.

I claim as my invention:

1. An adjustable nozzle comprising a hollow body member adapted to be connected at its rear portion to a fluid conduit, a head rotatably mounted on the front end of said body member and having a central passageway communicating with the bore of said body member, a shoulder projecting inwardly into said central passageway, said passageway being outwardly flared forwardly of said shoulder, a flow control member mounted in said central passageway, means for axially moving said flow control member in response to rotation of said head relative to said body member, said means including a tail portion carried by said head and extending axially therefrom to the interior of said hollow body member, said tail portion being rotatably journaled in said hollow body member and said tail portion and said body member having mating frusto-conical sealing surfaces, resilient means interposed between said head and said body member to urge said frusto-conical sealing surfaces into fluid sealing engagement, said flow control member having an enlarged portion on the front end thereof disposed in said control passageway forwardly of said shoulder, said flow control member also having an annular abutment surface thereon disposed rearwardly of said shoulder, whereby the axial movements of said flow control member in either direction are limited and fluid flow cutoff, by the respective engagements of said

shoulder with said enlarged portion or with said abutment surface, and at intermediate axial positions of said flow control member said enlarged portion cooperates with said outwardly flaring surface to produce an adjustable spray.

2. An adjustable nozzle comprising a hollow body member, means for connecting the bore of said body member in communication with a fluid source, said body member having a pair of diametrically opposed, axially extending grooves in said bore, a support member bottomed in said grooves and extending transversely across said bore, a centrally passaged nozzle head rotatably supported by said body member with said central passage communicating with said bore, a flow control member mounted in said central passage, a slot in said flow control member slidably receiving said supporting member, thereby permitting axial movement but preventing rotation of said flow control member, threadable means cooperating between said nozzle head and said flow control member for axially shifting said flow control member by rotation of said nozzle head, and means on said flow control member cooperating with said central passage to provide a variable spray annular orifice, said orifice being variable as a function of the axial position of said flow control member.

3. An adjustable nozzle comprising a hollow body member internally threaded at its rear end for coupling to a fluid source, the bore wall of said body member having at least one axially extending groove forwardly of said threaded portion, a nozzle head having a central passage and an internally threaded tail portion rotatably journaled in the forward portion of said body member bore with said central passage aligned therewith, a fluid flow control member having a bulbous head front portion, an externally threaded intermediate portion, and an axially slotted rear end portion, said fluid flow control member being mounted in said central passage of said nozzle head and threadably engaged in said tail portion, and a bar transversely disposed in said slotted end portion of said fluid flow control member and projecting into said groove, whereby rotation of said nozzle head produces axial shifting of said fluid flow control member, said central passage having an outwardly flaring wall surface in the front end thereof adjacent said bulbous head, whereby a variable spray is produced by the axial shifting of said fluid flow control member.

4. The combination defined in claim 3 wherein in said intermediate threaded portion of said fluid control member is non-circular in cross section to permit fluid flow through the cooperating threads.

5. An adjustable nozzle comprising a hollow body member internally threaded at its rear end for coupling to a fluid source, the bore wall of said body member having at least one axially extending groove forwardly of said threaded portion, a nozzle head having a central passage and an internally threaded tail portion rotatably journaled in the forward portion of said body member bore with said central passage aligned therewith, a fluid flow control member having a bulbous head front portion, an externally threaded intermediate portion, and an axially slotted rear end portion, said fluid flow control member being mounted in said central passage of said nozzle head and threadably engaged in said tail portion, and a bar transversely disposed in said slotted end portion of said fluid flow control

member and projecting into said groove, whereby rotation of said nozzle head produces axial shifting of said fluid flow control member, an inwardly projecting shoulder in said central passageway disposed rearwardly of said bulbous head, said passage being outwardly flared forwardly of said shoulder, and a flange on said fluid flow control member disposed rearwardly of said shoulder, whereby axial movement of said fluid flow control member is limited between two flow interrupting positions and a variable spray is produced intermediate said limiting positions.

6. An adjustable nozzle comprising a hollow body member internally threaded at its rear end for coupling to a fluid source, the bore wall of said body member having at least one axially extending groove forwardly of said threaded portion, a nozzle head having a central passage and an internally threaded tail portion rotatably journaled in the forward portion of said body member bore with said central passage aligned therewith, a fluid flow control member having a bulbous head front portion, an externally threaded intermediate portion, and an axially slotted rear end portion, said fluid flow control member being mounted in said central passage of said nozzle head and threadably engaged in said tail portion, and a bar transversely disposed in said slotted end portion of said fluid flow control member and projecting into said groove, whereby rotation of said nozzle head produces axial shifting of said fluid flow control member, an inwardly projecting shoulder in said central passageway disposed rearwardly of said bulbous head, said passage being tapered inwardly forwardly of said shoulder and then flared outwardly, and a flange on said fluid flow control member disposed rearwardly of said shoulder, whereby axial movements of said fluid flow control member are limited between two flow interrupting positions and a cylindrical stream or a variable spray is produced intermediate said limiting positions.

7. An adjustable nozzle comprising a hollow body member having a generally cylindrical bore, means for connecting the rear end of said bore in communication with a fluid source, an internally projecting shoulder at the front end of said bore defining a rearwardly facing seating surface, said bore having a pair of diametrically opposed, axially extending grooves in the wall

flared outwardly, and a seat on said fluid flow control member disposed rearwardly of said shoulder, whereby axial movements of said fluid flow control member are limited between two flow interrupting positions and a variable spray or cylindrical stream is produced intermediate said limiting positions.

8. An adjustable nozzle comprising a hollow body member having a generally cylindrical bore, 10 means for connecting the rear end of said bore in communication with a fluid source, an internally projecting shoulder at the front end of said bore defining a rearwardly facing seating surface, said bore having a pair of diametrically opposed, axially extending grooves in the wall thereof rearwardly of said shoulder, a nozzle head having a central passage and an internally threaded tail portion rotatably journaled in said body member bore rearwardly of said shoulder, a forwardly facing seating surface on said nozzle head engaging said rearwardly facing surface in fluid sealing relationship, resilient means operating axially between said body member and said nozzle to urge said seating surfaces into engagement, a fluid flow control member 15 having a bulbous head front portion, an externally threaded intermediate portion, and an axially slotted rear end portion, said fluid flow control member being mounted in said central passage of said nozzle head and threadably engaged in said tail portion, a bar transversely disposed in said slotted rear portion of said fluid flow control member and having the ends thereof respectively projecting into said grooves, 20 whereby rotation of said nozzle head produces axial shifting of said fluid flow control member, an inwardly projecting shoulder in said central passageway disposed rearwardly of said bulbous head, said central passage being tapered inwardly forwardly of said shoulder and then flared outwardly, a seat on said fluid flow control member disposed rearwardly of said shoulder, whereby axial movements of said fluid flow control member are limited between two flow interrupting positions and a variable spray or cylindrical stream is produced intermediate said limiting positions, said body member having an annular spherical segment external surface, a fluid fitting 25 having a mouth defining an interior, annular spherical segment surface corresponding to that of said body member, and means for securing
